COMBINED CABINET AND CLOTHES RACK

John E. Borah, Penn Township, St. Joseph
County, Ind.

Application November 10, 1938, Serial No. 239,774

7 Claims. (Cl. 312—177)

This invention relates to a combined cabinet and clothes rack.

In household laundering, one of the objectionable features is the necessity for hanging the clothes to dry on an elongated inconvenient clothesline, usually located out-of-doors or in a basement. A long line is necessary to give adequate hanging facilities, and the line must be placed at a substantial and inconvenient height 10 to permit a person to pass the line by stooping under the clothes and to permit a person to walk thereunder when not in use. There are many disadvantages to this method of drying clothes as commonly appreciated and encountered by housewives.

It is the primary object of this invention to provide means, convenient and accessible in use, carried by a cabinet, and utilizing a minimum amount of space, for hanging clothes to dry.

20 A further object is to mount in the cabinet of a washing machine, space heater, or the like, a plurality of normally retracted and concealed elongated elements which are horizontally extensible to exposed projecting relation to form a 25 rack upon which articles of clothing and the like may be hung to dry.

25 A further object is to provide an elongated rigid member with a mounting carried by a cabinet for slidably supporting said member in selected concealed or projecting relation to the cabinet.

30 Other objects will be apparent from the description and appended claims.

In the drawings:

Fig. 1 is a perspective view of a cabinet having 35 a clothes rack, with certain of the rack parts shown in extended position in dotted lines.

Fig. 2 is a fragmentary vertical sectional view 40 of a modified arrangement of cabinet and clothes rack.

Fig. 3 is a fragmentary vertical sectional view 45 illustrating still another embodiment of my invention.

Fig. 4 is a fragmentary sectional view taken on 50 line A—A of Fig. 1 and illustrating the construction and method of mounting one form of the clothes rack.

Fig. 5 is a fragmentary view similar to Fig. 4 and illustrating the clothes rack in extended 55 position.

Fig. 6 is a fragmentary sectional view taken on line B—B of Fig. 1 and illustrating the construction and method of mounting another form of clothes rack.

Fig. 7 is a fragmentary view similar to Fig. 6

and illustrating the clothes rack in extended position.

Fig. 8 is a fragmentary horizontal sectional view illustrating another embodiment of my invention.

Figs. 9, 10 and 11 are perspective views illustrating my invention applied to a space heater, washing machine, and kitchen wall cabinet, respectively.

Fig. 12 is a fragmentary sectional view taken 10 on line 12—12 of Fig. 10.

Referring to the drawings, which illustrates the preferred embodiment of my invention, the numeral 10 designates a conventional cabinet or enclosure of a washing machine, space heater, or 15 the like, having front and rear walls 11 and end walls 12.

A plurality of elongated hollow tubes 15 extend in parallel horizontal relation between the front and back walls 11 of the cabinet at the upper 20 end thereof and above the operating mechanism housed in the cabinet. The opposite ends of tubes 15 are internally screw threaded. A threaded member 16 passing through a suitable opening in back wall 11 is threaded in one end of tube 15, 25 said member 16 having an enlarged head 17 bearing against wall 11 around the opening therein to retain and lock the rear end of the tube in operative supported relation to said wall and to seal said opening. An externally screw threaded 30 tubular member 18 passes through a suitable opening in the front cabinet wall and is screw threaded in the front end of tube 15, said member 18 having an annular outwardly projecting flange 19 seating against the front wall of the 35 cabinet. Within the tube 15 is mounted an elongated rod 20 having a close but sliding fit with member 18 and having an enlargement 21 on its inner end which has a close but sliding fit within tube 15. A head 22 is mounted on the outer end 40 of the rod 20 and normally seats against flange 19.

A plurality of elongated hollow tubes 25 extend in parallel horizontal relation between the end walls 12 of the cabinet adjacent the upper end thereof and adjacent and perpendicular to tubes 15. Openings are formed in each wall concentric with the adjacent ends of each tube 25. Externally screw threaded tubular members 26, each having an outwardly projecting annular flange 27, pass through said openings and are threaded 45 into the ends of tubes 25 to bring flanges 27 into bearing engagement with the cabinet walls and thus lock the tubes 25 in place. Within each tube 25 is mounted a pair of tubular members 28 each having an enlargement 29 at its inner end which 50

55

has a close but sliding fit within tube 25. The outer ends of the tubular members 28 normally terminate within members 26 in inwardly spaced relation to the adjacent cabinet wall, said members 28 having a close but sliding fit in members 26. An inwardly projecting annular flange 30 is formed at the outer end of each member 28. A rod 31 fits in each member 28, having a close but sliding fit in flange 29. The inner end of each rod 31 is enlarged at 32 for a close sliding fit in member 28, and the outer end of each rod 30 mounts a head 33 normally bearing against annular flange 27.

With this construction, the clothes racks, when in their normal retracted positions illustrated in Figs. 4 and 6, are substantially concealed, do not detract from the appearance of cabinet 10, and do not interfere with normal use of or access to the device, as washing machine or space heater, enclosed in the cabinet. When the clothes racks are to be used, they are extended as illustrated in Figs. 5 and 7. The rods 20 are extensible for substantially their full lengths, or to an extent substantially equal to the spacing of walls 10. The rods are fully and adequately supported in extended position by the double bearing between the same and parts 18 and between enlargements 21 and tube 15. The outward extension of the rods is limited by engagement of enlargements 21 thereof with members 18. The heads 22 form means for conveniently gripping the rods for such extension.

The other rack units operate in substantially the same manner, except that the projecting portion thereof is substantially twice the length of the rod 31. When rod 31 is pulled out by means of head 33, the enlargement 32 thereof engages shoulder 30 on the outer end of intermediate tubular member 28 which may in turn be pulled out until its enlargement 29 engages member 26. A double bearing for effectively supporting each set 25, 28 and 28, 31 of the cooperating parts in horizontal position when extended is provided by the close fits between the respective enlargements and restrictions on the ends of the telescoping parts. It will thus be seen that the effective projecting length of each of these units is substantially equal to the spacing of cabinet walls 12 between which they are mounted. Both rack units are placed at a convenient height for the housewife, and yet provide adequate spacing above the floor for the clothes to hang clear thereof. Likewise, the units may be quite closely spaced, to afford air space between clothes hung thereon, and at the same time their aggregate length will be the equivalent of a long clothesline. This can all be accomplished in a very small area or space without interfering with the normal use of the room 60 in which the device is located.

This invention is susceptible of use in connection with cabinets of many types and for many purposes. One of these embodiments is illustrated in Fig. 2 wherein the cabinet or housing 65 is open at its top and is closed by a removable cover 40. The units 15 and 25, of the construction above described, are mounted within a crowned portion of the cover in spaced relation above the lower open end or margin 41 of the cover which rests upon or engages the top of the cabinet. In this way, the units are removable with the cover, and do not interfere with access through the top of the cabinet.

An embodiment especially adapted for use with 75 space heater cabinets is illustrated in Fig. 3.

Here the top of the cabinet is normally open at 45 for heat discharge and radiation. The units 15 and 25, when spaced just below the top of the cabinet, render use of a grill unnecessary, since their location and arrangement permits them to 5 accomplish the same function as a grill without detracting from the appearance of the cabinet.

An embodiment especially adapted for use with circular cabinets is illustrated in Fig. 8. In this arrangement, a concentric frame member 48 10 depends from the top of the cabinet to support the inner ends of the tubes 15 of the rack construction illustrated in Fig. 4, the construction being otherwise the same as described above.

The modified embodiment illustrated in Fig. 15 12 is particularly applicable to installation of the types illustrated in Figs. 10 and 11. A shallow chamber is provided between spaced horizontal parts 50 and 51 closed at its outer edges by vertical wall 52 having an opening therein 20 to slidably receive a rod 53 with a close fit. A guide 54 spaced inwardly from wall 52 receives rod 53, and a stop 55 spaced from the inner end of the rod a distance substantially equal to the spacing between upper and lower walls 50 and 25 51, is adapted to engage guide 54 when the rod is outwardly extended. By this construction the number of parts is reduced to a minimum, the rear projecting end of the rod insuring proper positioning of the extended rod, though slightly 30 tilted, by its engagement with top 50 when extended and with bottom 51 when retracted. In the event the guide 54 limits vertical as well as horizontal movement of the rod, the stop 55 may be placed at the extreme inner end of the 35 rod, as is obvious.

I have illustrated the tubes 15 and 25 and their associated parts as being of circular cross-section; but I do not intend to limit myself thereto, as tubes of square or other cross-section 40 may obviously be used in the arrangement and relation shown and described.

I claim:

1. The combination with a cabinet having a pair of opposed vertical walls each having an 45 opening, of an elongated horizontal tube, securing members each passing through an opening and mounted within an end of said tube, at least one of said securing members having a passage therethrough, an elongated member having a 50 close sliding fit in said last named securing member, an enlargement on the inner end of said elongated member having a close sliding fit in said tube, and an enlarged head on the outer end of said elongated member, said head being 55 positioned exteriorly of said cabinet and normally positioned adjacent the outer surface thereof.

2. The combination with a cabinet having opposed openings in horizontal alignment adjacent the upper end thereof, a rigid elongated hollow member extending between said openings, means for mounting the ends of said member on said cabinet, at least one of said mounting means having a passage therethrough, a second rigid elongated hollow member slidable within said first member, a third elongated member slidable in said second member, means cooperating with said mounting means for limiting outward sliding of said second member in said first member, means for limiting outward sliding of said third member in said second member, said last named means cooperating with said members to hold said members in alignment when extended, and a head on said third member exteriorly of and normally bearing against said cabinet.

3. The construction defined in claim 2, wherein the means for limiting outward movement of said members comprises said mounting means and an inwardly projecting element at the outer 5 end of the second member each having a close sliding fit around the second and third members, respectively, and an enlargement on the inner ends of the second and third members having a close sliding fit in the first and second members, respectively.

4. The combination with a cabinet including a removable cover having vertical marginal walls, a pair of said walls in opposed relation, each having an opening, of an elongated horizontal 10 tube, securing members each passing through an opening and mounted within an end of said tube, at least one of said securing members having a passage therethrough, an elongated member having a close sliding fit in said last named 15 securing member, an enlargement on the inner end of said elongated member having a close sliding fit in said tube and an enlarged head on the outer end of said elongated member, said head being positioned exteriorly of said cabinet 20 and normally positioned adjacent the outer surface thereof.

5. The combination with a cabinet having a pair of opposed vertical walls, of a horizontal tube, means for securing the ends of said tube 25 to said walls within and adjacent the top of said cabinet, at least one of said walls having an opening communicating with the interior of said tube, an elongated member slidably within said

tube and having a head positioned outwardly of and normally bearing against the outer surface of said cabinet, the securing means adjacent one wall serving to limit the outward sliding of said elongated member and cooperating with said tube and member to maintain said member in horizontal position when extended. 5

6. The combination with a cabinet having opposed horizontally aligned openings adjacent the upper end thereof, a horizontal, rigid, elongated, 10 hollow member secured to said cabinet with the ends thereof communicating with said openings, a pair of rigid elongated members slidable within opposite ends of said first member and each 15 having a head positioned exteriorly of said cabinet, and cooperating means between each of said second members and said first member for limiting opposite outward extension of said second members and maintaining said members in alignment when extended, an element of said last named means also serving to secure said hollow member to said cabinet. 20

7. The combination with a cabinet having an opening in its top and a plurality of openings in a vertical wall thereof, of a plurality of longitudinally shiftable elongated members each extending through one of said last named openings, and supports within said cabinet each guiding and positioning a member relative to said cabinet, said supports constituting a grill 25 30 spanning said first named opening.

JOHN E. BORAH.
